R. THOMAS & SONS COMPANY, OF EAST LIVERPOOL, OHIO, A CORPORATION OF
OHIO.

MACHINE FOR HEADING PORCELAIN TUBES AND THE LIKE.

Application filed March 4, 1922. Serial No. 541,250.

To all whom it may concern:

Be it known that we, ALBERT G. MASON and LORENZO C. BUCKLEY, citizens of the United States of America, both residing at 5 Lisbon, in the county of Columbiana and State of Ohio, have invented certain new and useful Improvements in Machines for Heading Porcelain Tubes and the like, of which the following is a specification.

10 Our invention relates to machines for heading porcelain tubes and the like. The object of our invention is to provide a machine for this purpose which is automatic and rapid in its operation, and involves no 15 hazard to the attendant.

In the accompanying drawings—

Fig. 1 is a broken side elevation of a machine in which our invention is embodied in one form;

20 Fig. 2 is a similar view showing the machine in another position;

Fig. 3 is an enlarged side elevation of the die portion of the machine drawn to a larger scale, and illustrating the position of the 25 parts just in advance of the heading operation;

Fig. 4 is a similar view showing the position of the parts on completion of the heading operation;

30 Fig. 5 is a plan of the machine on the scale used in Fig. 1;

Fig. 6 is an enlarged section on the line 6—6, Fig. 1;

Fig. 7 is a section on the line 7—7, Fig. 35 6; and

Fig. 8 is a perspective of the finished tube.

The apparatus is susceptible to various modifications in details of construction and arrangement of parts, and that shown is 40 merely an illustrative embodiment of the underlying features of the invention. As

shown, it comprises a skeleton table or bed 10 supported on standards 11 and 12, to which it may be secured in any suitable way, as by bolts 13. Mounted in fixed position and spaced apart on the bed 10 are oppositely faced dies 14 and 15 having their remote ends cupped at 16 and 17 respectively. Cooperating therewith are reciprocating forming dies 18 and 19, the faces 20 of

50 which are shaped to complement the shaped ends of the stationary dies 14 and 15 to form the heads 21 of the tube blanks 22. The stationary dies 14 and 15 are longitudinally

pierced at 23 and 24 to accommodate the 55 tube blanks 22 during the head-forming operation.

The forming dies 18 and 19 are provided with base flanges 25 and 26, by which they are bolted to slide bars 27 and 28. The base 60 flanges are extended outwardly to rest on the longitudinals of the bed 10 and assist in supporting the slides thereon. Reciprocating motion is imparted to the dies 18 and 19 from the driving shaft 29 through the 65 crank arm 30 and link 31 connected at one end to the crank arm, and at the other end to a downwardly extending bracket 32 at one end of the slide. The shafts 29 may be driven in any suitable fashion, as by 70 means of a pulley 33 and driving belt 34. The stroke of the slide is of a length predetermined with respect to the fixed dies 14 and 15, which may be adjustably secured 75 on the bed 10 by means of their clamping bolts 35 in such position that at the ends of the slide strokes in opposite directions, one or the other of the forming dies is brought into juxtaposition to its cooperating fixed die 14 or 15, to form a head on 80 the tube blank.

Associated with the die pairs 14-18 and 15-19 are feed tables 36 and 37, each channeled to the shape of a tube blank 22, and so positioned that it presents the blank with its axis in alignment with the dies. Each of the forming dies 18 and 19 is provided with an axially arranged and forwardly extending pick-up pin 38, or 39, adapted, as the forming die travels toward its cooperating stationary die, to enter the tubular blank 85 on the associated feed table and carry the blank toward and guide it into the fixed die 14 or 15, as the forming die approaches 90 the latter.

The feed tables 36 and 37 are arranged between the longitudinals of the bed 10 and are supported below the latter in any suitable manner. As here shown each table is carried by a pair of links 40 and 41 pivoted 100 at one end to a frame standard 11 or 12, and at their other ends to the bar 42 or 43 to which the feed table proper is bolted. Cross pins 44 and 45 passing through the bars are so located as to limit the upward movement 105 of the bars 42 and 43, and thus insure the presentation of the tubular blanks thereon in accurately predetermined position with

respect to the pick-up pins 38 and 39 of the forming dies. Springs 46 and 47 attached at their upper ends to the bed of the machine, and at their lower ends to the bars 42 and 43, tend constantly to lift the tables to feed position. Inasmuch as the tables lie in the path of the movable dies, cam extensions 48 and 49 are provided against which the lower edges of the forming dies 5 impinge on their working strokes and depress the tables out of constructing position. The dies are also provided with tail pieces 50 and 51, which overlie the tables and maintain the latter depressed during the 10 completion of the working stroke of the dies. Upon the return stroke, the tables automatically rise under the action of springs 46 and 47 to feed position, as soon as cleared by the dies.

15 While the tube blanks may be placed upon the feed tables by hand, an automatic delivery thereto is preferred. Any suitable trip device for this purpose may be employed. As here shown, we have associated 20 with each table a hopper chute 52 and 53 in which the tube blanks 22 may be placed by hand or automatically. At its lower end each hopper or chute has associated therewith a trip comprising a pair of detaining 25 fingers 54 movable toward and away from the stationary delivery apron 55 at the lower end of the chute. The fingers 54 are pivoted at 56 and 57 to crank arms 58 and 59 secured to a spindle 60. At one end of the 30 latter is arranged a spring 61 by which the spindle 60 is normally held in a position to retract the fingers 54 into engagement with the tube blank at the lower end of the chute. At its opposite end the spindle carries a trip 35 lug 62 adapted to be engaged by a pawl 63 pivoted on a stud 64 on a bracket 65 secured to the movable die 18 or 19. A spring 66 permits the pawl to yield on the working 40 travel of the die, but presents the cam end 45 67 of the pawl in position to engage the side of the trip lug 62 on the spindle 60, and thus to oscillate the latter sufficiently to lift the detaining fingers 54 out of engagement with the tube blank. The latter now freed, 50 rolls down the apron 55 and drops upon the feed table 36 or 37, by which it is supported in position for engagement by the pick-up pin 38 or 39 on the succeeding working travel of the die. Stop lugs 540 associated 55 with the detaining fingers 54 rise with the latter and engage and hold the tube blank next to that freed, until the return of the fingers 54 to detaining position, when the lugs sink out of stop position and the blanks 60 advance in the chute.

To form an abutment for the tube blank in the stationary die during the forming operation, as well as an automatic discharge for the tubes after the heading operation is completed, a rod 68 is provided. This is

supported at its opposite ends in the passages 23 and 24 in the stationary dies 14 and 15, and has a diameter substantially corresponding to the latter. Adjustably secured to the rod 68 by set screw 69 is a saddle 70 having a foot piece 71 adapted to rest freely upon the slides 27 and 28. On one or both sides of the saddle and carried by the foot piece 71 are arranged cushioning springs 72 and 73. Cooperating with the saddle 70 are 75 studs 74 and 75 fixed on the slide bar 28 and adapted to freely engage one or the other of said springs, during the working strokes in opposite directions, to shift the saddle, and thus the push rod 68, longitudinally in the 80 stationary dies 14 and 15. The spacing of the stationary dies is such that when one or the other of the studs 74 or 75 picks up the saddle 71, the saddle is shifted in the direction of the working stroke and the rod 68 is thus retracted in the stationary working die. In Figs. 3 and 4 the operation of the stud 75 is illustrated. It will be noted that in the position indicated in Fig. 3 the tube blank 22 has entered the stationary die 15, 85 and the rod 68 has been shifted to the right by the stud 75, which is in engagement with the end of the spring 72. The saddle 70 has been shifted to the right and abuts against the die 14 so that its further travel in this 90 direction is prevented. The stroke of the slides 27 and 28 in the same direction is not yet complete. A slight further movement in the same direction is necessary to bring the forming die 19 into juxtaposition to the stationary die 15 to shape the head 21 on the tube. The spring 72 permits the stud 75 to advance during this final portion of the 95 working stroke, while the rod 68 is held stationary and forms the abutment for the tube 100 22 during the further advance of the die 19. Inasmuch as the tube blank abuts the now stationary rod 68, the forming die 19 displaces the material at the opposite end 105 of the blank into the die recesses, and shapes 110 it into the head 21. (See Fig. 4.) On the working stroke of the slide in opposite direction, stud 74 picks up the saddle 70 and forces the rod 68 through die 15 and thus 115 expels the headed tube 22 therefrom, permitting it to drop from the die 15 into a re- 120 centacle 76 beneath the bed of the machine. The operation of the apparatus may be briefly resumed. Assuming the feed chutes 52 and 53 to be properly charged with tube 125 blanks 22, the machine is set in motion. As the slide travels toward the right, the blank supported on the table 37 is engaged by the pick-up pin 39 and forced from the table as the die 19 advances. Simultaneously, the die 18 traveling to the right trips the feed mechanism for the chute 52 and a blank is fed to the table 48. As the die 19 passes over the table 37 it is depressed and the blank previously supported thereon is now 130

carried by the pick-up pin 39 toward the stationary die 15. As the slide advances, the stud 75 thereon engages the saddle 70 and pushes the latter to the right, thus shifting the push rod 68 from obstructing position in the channel of the die 15. The tube blank now enters the die 15 and bears against the end of the rod therein as the saddle is halted by the impingement of the 55
 10 saddle 70 against the stationary die 14. The final advance of the die 19 while the inner end of the tube blank 22 rests against the now stationary rod 68, forces the outer end of the tube into the die apertures and shapes 15 the tube head. On the reverse stroke the forming die 19 moves away from the die 15, while the die 18 picks up the tube blank on the table 36 and advances it toward the stationary die 14. Simultaneously the stud 20 74 picks up the saddle 70 and advances it with the push rod 68 to the left, thus forcing out the formed tube in the die 15 and clearing the way for the tube blank to enter the stationary die 14. It is obvious that 25 the attendant has merely to see to it that the feed chutes 52 and 53 are properly filled with tube blanks, and that the mechanism is working properly. Inasmuch as the pick-up and feed of the blanks to the dies is automatic, there is no danger of injury to the 30 operator.

Various modifications in detail and arrangement of parts will readily occur to those skilled in the art, which do not deviate from what we claim as our invention. 35

We claim—

1. In a tube-heading machine, a stationary die, a movable die cooperating therewith, a feed table adapted to support a tube blank 40 in substantial alignment with said dies, and means associated with the movable die for picking up the blank from said feed table and introducing it into the stationary die, together with means for depressing the feed table and holding it depressed during the working travel of the movable die.
2. In a tube-heading machine, a stationary die, a movable die cooperating therewith, a feed table adapted to support a tube blank 45 in substantial alignment with said

dies, and means associated with the movable die for picking up the blank from said feed table and introducing it into the stationary die, together with means for depressing the feed table and holding it depressed during 55 the working travel of the movable die, and means for returning said table to feed position during the return stroke of the movable die.

3. In a tube-heading machine, a pair of 60 stationary dies, a pair of movable forming dies cooperating therewith, a reciprocating slide with which said movable dies are associated, a plunger working in said stationary dies, and a lost motion connection between 65 said slide and plunger to shift the latter in the stationary dies to expel a formed tube in one of the latter while bringing said plunger to posititon to act as an abutment for the tube blank in the other 70 stationary die, substantially as described.

4. In a tube-heading machine, a pair of 75 stationary dies, a pair of movable forming dies cooperating therewith, a reciprocating slide with which said movable dies are associated, a plunger working in said stationary dies, and a lost motion connection between 80 said slide and plunger to shift the latter in the stationary dies to expel a formed tube in one of the latter while bringing said plunger to posititon to act as an abutment for the tube blank in the other stationary die, said lost motion connection including a 85 spring cushion permitting motion by the slide on its working stroke after the plunger has been halted.

5. In a tube-heading machine, a pair of spaced stationary dies, a pair of movable forming dies cooperating therewith, a plunger working in said stationary dies, a stop 90 associated with said plunger and engaging said stationary dies to limit the movement of the plunger, and means associated with the movable dies to reciprocate said plunger, 95 substantially as described.

In testimony whereof we have signed our names to this specification.

ALBERT G. MASON.
LORENZO C. BUCKLEY.
